UNITED STATES PATENT OFFICE

90,467

DESIGN FOR AN ACETYLENE LAMP

James H. Horsley, Chicago, Ill., assignor to
Shanklin Manufacturing Co., Springfield, Ill., a
Corporation of Illinois

Application November 28, 1932. Serial No. 46,191

Term of patent 14 years

To all whom it may concern:

Be it known that I, JAMES H. HORSLEY, a citizen of the United States, residing at Chicago, in the county of Cook and State of Illinois, have invented a new, original, and ornamental Design for an Acetylene Lamp, of which the following is a specification, reference being had to the accompanying drawing, wherein

Fig. 1 is a side elevational view of an acetylene lamp embodying the design; and

Fig. 2 is a front elevational view of the same.
I claim:

The ornamental design for an acetylene lamp substantially as shown.

JAMES H. HORSLEY.
